G. E. NETTLETON,
INDICATOR FOR RUBBER MILLS.
APPLICATION FILED MAY 6, 1916.

1,206,894.

Patented Dec. 5, 1916.

WITNESS:

S. S. Taylor, Jr.

INVENTOR

George E. Nettleton,

Ernest D. Hopkins
BY
HIS ATTORNEY

UNITED STATES PATENT OFFICE.

GEORGE E. NETTLETON, OF HARTFORD, CONNECTICUT, ASSIGNOR TO THE HARTFORD RUBBER WORKS COMPANY, A CORPORATION OF CONNECTICUT.

INVENTION OF INDICATOR FOR RUBBER-MILLS.

1,206,894.

Specification of Letters Patent.

Patented Dec. 5, 1916.

Application filed May 6, 1916. Serial No. 95,772.

To all whom it may concern:

Be it known that I, GEORGE E. NETTLETON, a citizen of the United States, residing at Hartford, county of Hartford, and State of Connecticut, have invented certain new and useful Improvements in Indicators for Rubber-Mills, of which the following is a full, clear, and exact description.

This invention relates to rubber mixing, warming and washing mills and has for an object to provide a device for assisting the operator in maintaining the rolls parallel and spaced a definite distance apart.

Unskilled laborers are usually employed to operate rubber mills. Great difficulty is experienced in getting these workmen to keep the rolls parallel with each other. Often-times they will operate the mill with the rolls disposed obliquely to each other and this does not produce the desired kneading of the rubber batch. Furthermore the rolls are sometimes set so far apart that when a new batch of hard rubber stock is put in the mill the shock causes the breaking of the rolls and in some cases even causes breaking of the mill frame and other parts. To overcome these disadvantages, the present invention provides indicators which are operated by the adjusting screws of the mill rolls to indicate to the workman the exact amount of opening between the rolls, so that guess work will be obviated and the operator will have no excuse for running the mill with the rolls not parallel, or spaced too far apart.

With the above and other objects in view, the invention consists in certain novel details of construction and combinations of parts hereinafter fully described and claimed it being understood that various modifications may be resorted to within the scope of the appended claim.

In the accompanying drawing forming part of this specification, Figure 1 is an end elevation of a mill equipped with the indicator. Fig. 2 is a plan view of the parts shown in Fig. 1.

Referring now to the drawing in which like characters of reference designate similar parts, 10 designates rolls, 11 the bearings thereof, 12 the frame, and 13 the adjusting screws for the bearings, all of these parts being of the usual and well-known rubber

mill construction. As usual, the rolls are run with a slight space existing between them, this space being determined by the extent to which the adjusting screws 13 are backed out from their respective threaded openings in the frame.

In carrying out the invention, I secure a collar 14 upon each adjusting screw, the collar being formed of two halves detachably secured together by a screw 15. Each collar is provided with a peripheral scale formed of spaced circular division marks 16 scored upon the collar. Fixed to the mill frame above each collar is a pointer 17 which is adapted to register with the scale of the collar.

In assembling the parts the mill rolls 10 are first moved into contact with each other by screwing tight the adjusting screws 13 of one of the rolls. The collars 14 are then adjusted longitudinally of and bolted upon the adjusting screws of said roll so that their outer end faces 18 are flush with the ends of the pointers 17. Said adjusting screws 13 are now backed out sufficiently from the mill frame to provide the desired space between the mill rolls, this movement of the screws causing the division marks on the scales to become visible beyond the pointers and indicate the amount of space between the mill rolls.

By reading the scales when adjusting the mill rolls, the workman is enabled to know definitely the amount of space existing between the ends of the mill rolls, and by making sure that the same number of division marks are visible on each collar beyond the respective pointer, he may know positively that the rolls are parallel. Since any movement of the adjusting screws permits of a corresponding space existing between the mill rolls, the workman need only manipulate the adjusting screws until a prescribed number of division marks of the scales appear beyond the pointers in order to space the rolls a required definite distance apart.

From the above it is evident that this invention provides an extremely simple device for assisting the unskilled operators of rubber mills to maintain the rolls parallel and spaced a definite distance apart.

Having thus described my invention, what

I claim as new and desire to protect by Letters Patent is:

A mill embodying a frame, rolls adjustable relatively to each other thereon, screws for adjusting the rolls, a collar formed in sections removably secured together and adjustable longitudinally of each screw and

having a peripheral scale, and pointers on the frame registering with the scales on the collars.

Signed at Hartford, Conn., this 19th day of April, 1916.

GEORGE E. NETTLETON.
